MAT FLEXIBILITY GAUGING DEVICE
Raymond T. Marshall, Kansas City, Mo., assignor to
Gustin-Bacon Manufacturing Company, a corporation
of Delaware

Filed Oct. 22, 1962, Ser. No. 231,893
6 Claims. (Cl. 73—100)

This invention deals generally with the evaluation of certain physical properties of mats made of bonded fibrous material, and it relates more particularly to apparatus for gauging the softness and flexibility of the mat.

One of the principal objects of the invention is to provide apparatus which is so constructed that accurate and consistent measurement of the softness and flexibility of a given mat can be obtained with a minimum of effort and despite variations in surface texture in the respective mats that are being subjected to such measurement.

Another object of the invention is to provide apparatus of the character described which lends itself readily to obtaining measurement in mats having different thicknesses without requiring any changes in the apparatus other than a simple adjustment of the location of certain of the mat-contacting elements.

Still another object of the invention is to provide apparatus of the character described which is of rugged construction, which can be operated with ease and facility, and which requires little or no skill or training for successful use.

Other and further objects of the invention together with the features of novelty appurtenant thereto will appear in the course of the following description.

In the accompanying drawing which forms a part of the specification and is to be read in conjunction therewith and in which like reference numerals indicate like parts in the various views:

FIG. 1 is a top plan view of a typical device embodying the invention, parts being broken away and in section for purposes of illustration;

FIG. 2 is a side elevational view of the device;

FIG. 3 is an enlarged fragmentary sectional view taken along line 3—3 of FIG. 2 in the direction of the arrows, the mat here being shown in solid lines;

FIG. 4 is a greatly enlarged fragmentary view looking endwise toward one of the mat-contacting elements;

FIG. 5 is a sectional view taken generally along line 5—5 of FIG. 4 in the direction of the arrows; and

FIG. 6 is a fragmentary sectional view taken along line 6—6 of FIG. 2 in the direction of the arrows.

Referring now to the drawings, and initially to FIGS. 1, 2 and 6, in its preferred form the device has a flat horizontal bed 10 supported on suitable feet 11. At one end of bed 10 are located a pair of laterally spaced uprights 12. These are bolted as at 13 to ears or flanges 14 formed integral with the bed. A horizontal tie rod 15 extends between and braces the uprights 12. The tie rod has threaded reduced diameter in portions 15a which extend through suitable apertures in the uprights and receive at their outer ends nuts 16. The tie rod, in addition to its bracing function, also serves as a convenient hand grip which may be utilized in moving the device from one location to another.

Positioned above and spaced from the bed 10 is a movable head or platen member 17, having a lower horizontal surface 17a and spaced, parallel upright side flanges 17b. The member 17 is supported from the uprights 12 by a parallelogram linkage now to be described.

Extending upwardly from member 17 near opposite edges thereof are the vertical hangers 18. These may be bolted as at 18a to the side flanges 17b. The hangers 18 are carried at the outer end of two superposed swing-

2

ing frames, the upper frame having the spaced parallel side members 19 and 20. The latter are secured together at their opposite ends by cross-pieces 21 and 22 respectively. The ends of cross-pieces 22 are provided with stub axles 22a which are journaled for rotation in suitable bearings 23 provided in and carried by uprights 12 near the upper ends thereof. In similar fashion, the ends of cross-pieces 21 are provided with stub axles 21a journaled in bearings 24 located near the upper ends of the hangers 18.

The lower frame has the parallel side members 25, 26 similar to the side members of the upper frame except that they are longer and extend beyond the uprights 12. The cross-pieces 27, 28 of the lower frame respectively have stub axles 27a, 28a journaled in bearings 29, 30 in the hangers 18 and uprights 12. The extending portions of side members 25, 26 support therebetween a counterweight 31. The counterweight is threadedly mounted for fore and aft adjustment on a threaded rod 32. The rod 32 is supported at its ends by securing them to cross-pieces 33, 34 secured inturn to and supported on the side members 25, 26.

It will be evident from the foregoing that the upper and lower frames are arranged and supported to swing in unison about the pivot axes defined by axles 22a, 28a remaining parallel to one another and maintaining the axles 21a, 27a in vertical alignment. Thus, as member 17 is raised or lowered, its lower surface always remains parallel with the surface of bed 10.

Turning now to FIGS. 2—5 inclusive, supported on bed 10 is a plate-like member 35 having on its upper surface two spaced parallel rows of upright projections or fingers 36, the rows being oriented generally parallel with the pivot axes of the support mechanism. As seen in FIG. 3, the projections in each row are spaced uniformly, there being in the preferred device four such fingers or projections in each row on the plate member 35. The fingers are each preferably provided with rounded tip portions which merge into a rectangular shank and are of uniform height. They are secured to the plate member by screws having countersunk heads 37, the screws extending through the plate member 35 from the underside and threaded into suitable tapped bores in the fingers.

Again referring to FIG. 3, it will be seen that the width of plate member 35 is slightly greater than that of bed 10. Secured to the opposite projecting edges of the plate as by bolts 38, are depending flanges 39. The flanges 39 have threaded therethrough set bolts 40 which are tightened against the adjacent sides of the bed 10 to immobilize the plate member and projection in a selected position on the bed.

A plate member 40 similar to plate member 35 is mounted to the underside of platen member 17 and secured thereto in identical fashion. Thus, it has flanges 41 carrying threaded set bolts 42 which are tightened against the confronting sides of the member 17. Plate 40 carries two rows of downwardly extending projections 43 identical to and mounted on member 40 in the same manner as projections 36 on the lower plate member 35. It will be noted, however, that while the upper and lower rows are in substantially vertical alignment, the projection 42 in the upper rows are staggered so that they lie spatially between the projections 36 and equidistant therefrom. Preferably the upper rows contain only three projections or fingers.

Returning again to FIG. 5 and also with reference to FIGS. 1 and 2, it will be observed that extending vertically between the near side members 20, 26 is a vertical link 44. The link 44 is pivotally connected near its opposite ends with said side members by shoulder bolts 45. The link is operably connected with a dial indicator 46 mounted to the near upright 12 by a bracket and bolt

47. The indicator is of conventional construction having a plunger 48 whose axial movement is registered on the dial. The end of the plunger rides on the flat upper end of link 44 and, consequently, it moves therewith. It will be understood that the dial is calibrated in increments proportioned to the spacing between bed 10 and the platen member 17.

In the operation of the invention, the counterweight is adjusted so that the platen member 17 remains stationary in a position spaced sufficiently above the bed 10 that a specimen M of mat (shown in broken lines in FIG. 2) can be freely inserted in flat condition between the upper and lower fingers with the tips of the respective fingers then brought down upon and lightly contacting the opposite faces of the mat. Care should be taken to so position the upper and lower rows of fingers on their respective supports (bed 10 and platen 17) that the rows are in vertical alignment. The reading at this time on the dial is noted and this is used as the "O" reading.

With the mat in position between the fingers, a predetermined weight W is then placed on the platen member 17. This weight may be of any arbitrarily selected value depending on the character of the mat with particular reference to its density and dimensional stability. A sufficiently heavy weight to obtain appreciable deflection in a very stiff mat should be used where the latter is the subject of the evaluation.

As shown in FIG. 3, under the load imposed by the weight, the mat is deflected from its flat condition with a concurrent closing of platen member 17 toward the bed 10. The displacement of the platen will be registered on and can be read from the dial and the flexibility or softness of the sample thus obtained.

While I have shown the use of staggered fingers to obtain the flexing resistance of the mat, it will be apparent that other forms of contacting elements such as staggered bars could be used.

From the foregoing it will be seen that this invention is one well adapted to attain all of the ends and objects hereinabove set forth together with other advantages which are obvious and which are inherent to the structure.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawing is to be interpreted as illustrative and not in a limiting sense.

Having thus described my invention, I claim:

1. Apparatus for evaluating the softness and flexibility of a fibrous mat, said apparatus comprising a stationary lower mat support bed having a plurality of upwardly projecting mat support members upon which said mat can be placed with one face of the mat resting upon and supported by said support members, an upper mat contacting member having a plurality of downwardly extending pressure members, said pressure members being offset from said support members whereby to contact the upper

surface of the mat at points intermediate the support members, means supporting said upper mat contacting member for up and down movement relative to said support bed, said means including mechanism operable to maintain the upper mat contacting member parallel with said support bed during said up and down movement, means for controlling the pressure exerted by said pressure member on the upper surface of the panel, and gauge means operable to measure the deflection of said upper mat contacting member from a predetermined position.

2. Apparatus as in claim 1 including means mounting said pressure members to said upper mat contacting member for selective displacement of said pressure members parallel with said upper mat contacting member.

3. Apparatus for evaluating the softness and flexibility of a fibrous mat, said apparatus comprising a bed with uprights at one end thereof, a vertically movable platen member spaced above said bed and generally parallel therewith, arm members connected with said uprights and supporting said platen member for up and down movement with respect to said bed, said arm members arranged to maintain said platen member substantially parallel with said bed during said movement, said platen member and bed each including a plurality of confronting oppositely directed projections for contacting opposite faces of a mat placed therebetween with the projection on said platen member offset from those of the bed, means for gravity biasing said platen member downwardly toward said bed and sensing means cooperating with said platen member and operable to measure the deflection of said platen member from a preselected position.

4. Apparatus as in claim 3 including means connecting at least one group of said projections with their associated platen member and bed for selective displacement transverse to the direction of movement of said platen member.

5. Apparatus for evaluating the softness and flexibility of a fibrous mat, said apparatus comprising a pair of substantially parallel members having confronting faces normally spaced from one another in substantially parallel relationship, a plurality of projections extending from each said face toward the other face, said projections on one face being offset from those of the other face, means supporting one of said members for movement toward and away from the other member, means operable to supply a force on one member tending to move it toward the other member, and sensing means operable to register the relative movement between said members under the influence of said force.

6. Apparatus as in claim 5 including means connecting the projections on at least one of said members with said member for selective adjustment on the member in a direction transverse to the direction of said movement.
